UNITED STATES PATENT OFFICE.

WILLIAM O. TAYLOR, OF LIMERICK, PENNSYLVANIA, ASSIGNOR TO WILDMAN MFG. CO.,
OF NORRISTOWN, PENNSYLVANIA, A CORPORATION OF PENNSYLVANIA.

STOP-MOTION FOR KNITTING-MACHINES.

1,254,087.

Specification of Letters Patent. Patented Jan. 22, 1918.

Application filed January 13, 1917. Serial No. 142,317.

To all whom it may concern:

Be it known that I, WILLIAM O. TAYLOR, a citizen of the United States, and resident of Limerick, Pennsylvania, have invented certain new and useful Improvements in Stop-Motions for Knitting-Machines, of which the following is a specification.

My invention includes features relating to a stop motion controlled by centrifugal force and therefore adapted to the type of knitting machine in which the needle cylinder is stationary and the yarn feed revolves, and it also includes features applicable to either the type of knitting machine just mentioned or to the type in which the yarn feed is arranged at one fixed point and the needle cylinder rotates.

The invention consists in the features and combination and arrangement of parts hereinafter described and particularly pointed out in the claims.

In the drawings;

Figure 1 is a plan view of part of a stop motion head adapted to circular knitting machines.

Fig. 2 is a side elevation.

Fig. 3 is a front view of the stop motion unit.

Fig. 4 is a plan view of a modified form of stop motion unit.

In these drawings 2 indicates a rotary bobbin stand, which as in usual practice may surmount the knitting head, not shown. 3 shows revolving yarn guides of which there may be any suitable number according to the number of yarns fed to the needles.

These parts rotate within a fixed frame ring 4. On a ring 5 revolving with the bobbin stand is pivotally mounted a member 6, 40 there being one of these for each yarn feed. These members are pivoted at 7 in brackets 8 fixed to the ring 5, and they are adapted to swing radially outward when free to do so under the action of centrifugal force.

45 These members may be of various forms and arrangements but in the particular form shown each consists of an arm extending upwardly from its pivot and having an outwardly extending lower portion 6*. When the yarn fails and allows the member 6 to swing outwardly under centrifugal force, as will be presently described, the portion 6* will swing down into the path of one of the projections 9 of a ring 10 which is sup-

ported on the fixed frame ring, and as member 6 is now in revolution about the axis of the knitting head the contact of the portion 6* with one of the studs 9 will impart to the ring 10 a rotary movement with the result that one of the radial studs 11 will be 60 brought against the letoff arm 12 forming the connection or a part of the connection to the letoff mechanism. When the machine is running with the yarn feeding properly the member or members 6 will be held in the 65 position shown at the left of Fig. 2 by the draft of the yarn in contact with a feeler finger or lever 13, which is connected with and holds the member 6 against the stress to which it is subjected until such time that 70 the yarn fails. This lever may assume different forms and arrangements but I find it of particular advantage to employ that illustrated in which a block 14 is mounted on a pin 15 fitted to a socket in the member 75 6, said connection forming a pivot for the block at the upper end of the said member 6. This block carries the feeler finger which includes in its construction a wire in the general form of a loop. Specifically described, 80 however, the loop has a straight side 13', the middle part of which is connected to the block and it has straight ends *a* *b*, the latter being longer than the end *a*, and it has a side *c* which for a part of its length is 85 straight and parallel with the straight side 13' but merges into a curved portion *d*, which connects with the straight end *b* by a rounded point or portion *e*, and it is within this rounded point that the yarn *x* is fed, 90 as indicated. The feeler finger or lever also includes a loop of wire *f* connected to the block 14, said loop embracing a fixed fulcrum 17 extending up from or formed with the bracket to which the member 6 is pivoted. This fulcrum lies close to the block 14, so that the length of the lever arm from the yarn engaging end at *e* of the feeler finger to the pivot 15 is much longer than the length of that arm of said feeler finger lever which lies between the said pivot 15 and the fixed fulcrum 17. The normal position of the parts of the stop motion unit is shown in Figs. 1 and 2 from which it will be seen that normally the draft of the yarn is about 100 at right angles to the direction in which the end *e* of the feeler finger must move in swinging away from the normal position

shown. By reason of the draft of the yarn being applied at or near the outer end of the long arm of the feeler finger lever slight draft or the draft of tender yarn on the 5 feeler finger lever will maintain it together with the centrifugal member 6 in normal position and against the stress to which the arm 6 is subjected by centrifugal force tending to make it fly outward.

- 10 As soon, however, as the yarn fails from breakage or from dropping off its sweep finger and the feeler finger is thereby relieved from the restraint of the draft of the 15 yarn, the member 6 being under stress, will immediately fly outwardly about its pivot bringing the projection 6^x into line with the projections 9 on the ring 10 and thus causing said ring to turn, and operate the letoff connection. In this action of 20 course the feeler finger turns about the fulcrum 17 and also of course about its pivot connection 15 with the member 6.

Compensation for variable speeds.

- 25 In some knitting machines changes in the number of revolutions per minute takes place automatically in accordance with the changes which automatically occur in the knitting and in order to take care of these 30 speed changes and make the stop motion unit self-compensating I provide a centrifugally actuated controller or compensator consisting of a weight or member 18 pivotally mounted at its upper end at 19 to the 35 post or standard 17' which has the fulcrum 17 at its upper end. This weight has its substantially horizontal upper edge underlying a pin 20 projecting laterally from an arm 21 at or near the upper free end of the 40 centrifugal member 6. The weight 18 is free to swing in a radial plane in respect to the stop motion head or in a plane substantially parallel to that in which the pivoted member 6 swings.

- 45 It will be understood that by the employment of this compensating or neutralizing weight 18 the stress applied by the feeler finger upon the yarn will remain constant in degree, notwithstanding the fact that at 50 times the machine, together with the stop motion unit rotates at high speed and at other times the machine runs at a low speed, the centrifugal force of course varying accordingly.

- 55 Now if the speed suddenly increases and the centrifugal arm 6 tends to fly outwardly at its upper end, the controller weight 18 will fly outwardly at its lower end causing its upper substantially horizontal edge to 60 rise in front of the pin 20, thus counteracting or neutralizing the outward movement or tendency of the centrifugal member 6, which action added to the restraining influence of the drag of the yarn on the feeler finger will prevent the increase in speed and

the higher centrifugal force from tripping the mechanism. The parts will be maintained in operative position until failure of the yarn occurs, whereupon the drag of the 70 yarn having ceased the feeler finger will no longer hold by its leverage action the centrifugal arm 6 and this will fly out because its power, due to centrifugal force, preponderates in respect to the restraining or neutralizing power of the controller and hence 75 the stop motion will be operated.

It will be noted that the pin 20 is slightly out beyond the vertical plane of the center of pivot 19. The member 6 is provided with an adjustable weight which may be of the 80 form shown in Fig. 4 at 22 but preferably it is of the form shown in Figs. 1, 2 and 3 at 22^a being pivoted at its lower end to the centrifugal member 6, and held in any desired position by spring washer 22^b. 85

The counteracting centrifugal governor 18 takes care of variations in speed but in order to take care of variations in the yarns used the adjustable weight 22^a is employed. By this a high feeler finger pressure may be 90 obtained upon heavy yarn, such as is required to insure prompt action upon the tripping mechanism, or a light feeler finger pressure may be obtained upon fine yarn which requires a light draft in order that it 95 may not be broken. By setting this weight in different angular positions the various requirements may be met.

I have found it desirable to provide a 100 guide 23 for the yarn at a point below the feeler finger and this I prefer to make vertically adjustable to increase or decrease the length of yarn lying between the feeler finger and the guide. This adjustment is shown at 24.

It will be understood that the yarn in resisting the pull of the feeler finger is drawn outwardly by it against this guide and that any further outward movement of the feeler finger will cause the yarn to be bent sharply at the guide and that the finger restraining effect of any given amount of yarn draft will be increased by reason of, first, change of angle in the direction of the yarn pull, and secondly, because as the yarn is bent more and more by still further movement of the finger an increasingly greater length of yarn is drawn in excess of the length of the finger movement.

Reverting to the form of the feeler finger 110 or lever above described it will be seen that I provide a pivot bearing for the feeler finger which is not likely to catch yarn or lint, ready clearing or cleaning of the pivot being rendered possible by simply lifting the finger with its pivot stem 15 from its socket. The closed loop formation a, b, c, d 115 and 13' retains the yarn against accidental unthreading.

The yarn is retained in the position of 120

maximum leverage upon the feeler lever during a comparatively wide range of movement of the feeler finger, this being due to the curved section *d* of the wire adjacent the 5 yarn engaging end *e* of the feeler finger lever, the effect of which is to prevent tripping off during temporary variations in yarn draft arising from imperfect winding on the bobbins or other causes which affect 10 the regular running, or changes in the tension of the yarn, but which are of such passing character as not to require stopping the machine.

In other words the centrifugal member 15 may have oscillation within certain limits and still be subjected to substantially the maximum leverage of the feeler finger by the yarn in contact with the arc-shaped or curved portion *d* thereof which will promptly act to restore the finger and centrifugal member to normal position upon the 20 passing of the temporary abnormal condition or variation.

The effect of the extension of the open 25 space at *y* within the feeler finger to a point on the opposite side of the pivot 15 thereof from that of the yarn engaging end is to avoid drawing off an unnecessary amount of slack yarn when tripping off takes place, because 30 the yarn is free to move into this rearwardly disposed recess and remains well in toward the center of the machine instead of being carried outwardly with the centrifugal member and feeler finger. Further, this 35 rearwardly disposed recess keeps the yarn at all times away from the point 15 where the feeler finger or lever is pivoted to the centrifugal member, thus avoiding entanglement of the yarn with the said pivot.

While I have described the feeler finger 40 or lever in connection with a centrifugal form of stop motion mechanism it will be understood that this feeler finger may be employed with forms in which the member 45 as *b* carrying the feeler finger may be subjected to stress in ways other than through centrifugal force.

It will be noted that the frame of the 50 stop motion head acts as the stop for determining the inward position of the feeler finger which bears thereon at the point *x'*.

For feeding a plating yarn together with a main yarn two stop motion units are required, the parts of one of these units being 55 set in respect to the location of the parts of the other unit, so that the yarn guiding ends of these feeler levers will lie close to each other.

The bracket which is detachably mounted 60 on the head and carries the swinging centrifugal arm and adjustable weight with the feeler lever at its upper end, and the neutralizing or compensating weight and also the fixed fulcrum constitutes a stop motion unit, 65 which may be applied to machines in any

number desired according to the number of feeds. This unit is complete in itself and needs no connecting up with other operative parts.

What I claim is:—

1. In combination in a stop motion for knitting machines, a letoff connection, a member under stress and thereby tending to move into position for operating the letoff connection, a fixed fulcrum, and a feeler 70 lever pivotally mounted at the upper end of said member and comprising a closed loop for receiving the yarn and a closed loop receiving the fulcrum on which the said feeler lever can turn and slide, substantially as described.

2. In combination in a stop motion for knitting machines, a letoff connection, a member under stress and thereby tending to move into position for operating the letoff 85 connection, a fixed fulcrum, and a feeler lever pivotally mounted on the said member, said feeler lever having a yarn receiving loop extending when in normal position laterally to each side of the pivotal mounting 90 and to each side of the plane of movement of the said member, said lever having a portion engaging the said fulcrum to turn thereon, substantially as described.

3. In combination in a stop motion for 95 knitting machines, a letoff connection, a member under stress and thereby tending to move into position for operating the letoff connection, a fixed fulcrum, and a feeler lever pivotally mounted on the said member, 100 said feeler lever having a yarn receiving loop forming one arm thereof, said loop having a portion to lie in rear of the pivotal mounting or between it and the axis of the machine, when the feeler lever swings to its 105 outward position, to thereby prevent drawing slack, a portion of said feeler lever engaging the fulcrum, substantially as described.

4. In combination in a stop motion for 110 knitting machines, a letoff connection, a member under stress and thereby tending to move into position for operating the letoff connection, a fixed fulcrum, and a feeler lever pivotally mounted on the said member, said 115 lever having a yarn receiving bearing extending on opposite sides of the pivotal mounting and offset in relation thereto to normally lie between said mounting and the axis of the machine, said feeler lever turning 120 about said fulcrum, substantially as described.

5. In combination in a stop motion for 125 knitting machines, a letoff connection, a member under stress and thereby tending to move into position for operating the letoff connection, a fixed fulcrum, and a feeler lever pivotally mounted on the said member, said lever having a yarn receiving bearing extending on opposite sides of the pivotal 130

- mounting and offset in relation thereto to normally lie between said mounting and the axis of the machine, said feeler lever turning about said fulcrum, said bearing being 5 curved to maintain the lever under a maximum restraining effect of the yarn during oscillations of the lever due to temporary causes.
6. In combination in a stop motion for 10 knitting machines, a let-off connection, a member under stress and thereby tending to move into position for operating the let-off connection, a fixed fulcrum, and a feeler lever pivotally mounted on the said member, said lever having a yarn engaging end 15 with a curved bearing for the yarn adjacent thereto to retain the yarn at or near the point of maximum leverage during oscillations of the lever due to temporary causes, substantially as described.
7. In combination in a stop motion for 20 knitting machines, a let-off connection, a member under stress and thereby tending to move into position for operating the let-off connection, a fixed fulcrum, and a feeler lever pivotally mounted on the said member, said feeler lever having its yarn engaging arm in the form of a closed loop of substantially rectangular shape and extending on 25 opposite sides of the pivotal mounting, the yarn guiding end of said arm being offset in relation to said loop and away from the pivotal mounting, substantially as described.
8. In combination in a stop motion for 30 knitting machines, a let-off connection, a member under stress and thereby tending to move into position for operating the let-off connection, a fixed fulcrum, and a feeler lever pivotally mounted on the said member, said feeler lever consisting of a block 35 having a pivot stem seated removably in a socket in the said member and wire arms carried by said block, substantially as described.
9. In combination in a stop motion for 40 knitting machines, a let-off connection, a member under stress and thereby tending to move into position for operating the let-off connection, a fixed fulcrum, and a feeler lever pivotally mounted on the said member, said feeler lever extending and working substantially in a horizontal plane and resting in connection with the said member by gravity and freely removable therefrom, substantially as described.
10. In combination in a stop motion for 45 knitting machines, a let-off connection, a member under stress and thereby tending to move into position for operating the let-off connection, a fixed fulcrum, and a feeler lever pivotally mounted on the said member, said lever having a block carrying the pivot and two wire loops, one extending laterally from the block and embracing the fulcrum 50 and the other extending across the inner end of the block, to points at opposite sides thereof, substantially as described.
11. In combination in a stop motion for 55 knitting machines, a let-off connection, a member under stress and thereby tending to move into position for operating the let-off connection, a fixed fulcrum and a feeler lever pivotally mounted on the said member and having an arm engaging the fulcrum and having also a yarn engaging arm, one portion of which extends on opposite sides of the plane of movement of the said member and is provided with a yarn receiving bearing extending at an inclination to the direction of movement of the member to 60 maintain the arm under a maximum restraining effect of the yarn during oscillation of the lever due to temporary causes.
12. In combination in a stop motion for 65 knitting machines, a member revolving with the machine subjected to centrifugal force tending to move it from a predetermined position, a let-off connection to be operated by said member, a second member also subjected to centrifugal force and opposing the movement of the first member from said predetermined position and a yarn guide carried by the first centrifugal member, whereby the draft of the yarn opposes the movement of 70 said member under centrifugal force, substantially as described.
13. In combination in a stop motion for 75 knitting machines, a member revolving with the machine subjected to centrifugal force tending to move it from a predetermined position, a let-off connection to be operated by said member, a second member also subjected to centrifugal force and opposing the movement of the first member from said predetermined position and a yarn engaging 80 portion carried by the first centrifugal member, whereby the draft of the yarn opposes the movement of said member under centrifugal force, substantially as described.
14. In combination in a stop motion for 85 knitting machines, a member revolving with the machine and pivotally mounted to swing radially under centrifugal force, a second centrifugal member also revolving with the machine and pivotally mounted to move radially outward under centrifugal force, said second member opposing the outward movement of the first member, a yarn engaging 90 portion carried by the member first mentioned to subject the same to the restraint of the draft of the yarn, and a let-off connection operated by the said first mentioned member, substantially as described.
15. In combination in a stop motion for 95 knitting machines, a member revolving with the machine and pivotally mounted to swing radially under centrifugal force, a second 100

- centrifugal member also revolving with the machine and pivotally mounted to move radially outward under centrifugal force, said second member opposing the outward movement of the first member, a yarn engaging portion carried by the member first mentioned to subject the same to the restraint of the draft of the yarn, and a let-off connection operated by the said first mentioned member, said first mentioned member being pivoted at or near its lower end and the second member being pivoted at a point to cause its lower end to swing outward under centrifugal force while its upper end opposes the outward movement of the upper end of the first member, substantially as described.
16. In combination in a stop motion for knitting machines, a member revolving with the machine and pivotally mounted to swing radially under centrifugal force, a second centrifugal member also revolving with the machine and pivotally mounted to move radially outward under centrifugal force, said second member opposing the outward movement of the first member, a yarn engaging member carried by the member first mentioned to subject the same to the restraint of the draft of the yarn, and a let-off connection operated by the said first mentioned member, said first mentioned member being pivoted at or near its lower end and the second member being pivoted at a point to cause its lower end to swing outward under centrifugal force while its upper end opposes the outward movement of the upper end of the first member, said yarn engaging member being in the form of a lever pivoted to the upper end of the first member and a fixed fulcrum with which said lever engages, substantially as described.
17. In combination in a stop motion for knitting machines, a let-off connection, a member revolving with the machine and movable under the influence of centrifugal force, a feeler finger in the form of a lever of the second order, that is with the centrifugal member pivotally connected thereto at a point nearer the fulcrum than the point where the draft of the yarn is applied to said lever to oppose the movement of the member so long as the proper yarn feed is maintained and a second centrifugal member opposing the movement of the first member and adding its restraining influence to that of the draft of the yarn, substantially as described.
18. In combination in a stop motion for knitting machines, a let-off connection, a member pivotally mounted to swing in a radial plane under the influence of centrifugal force, a feeler lever for engaging the yarn pivotally mounted at the upper end of said member and movable in substantially a horizontal plane, a fixed fulcrum for said feeler lever, and a second pivotally mounted member influenced by centrifugal force and opposing the outward movement of the first member and adding its restraint to the restraint of the draft of the yarn on the feeler lever, substantially as described.
19. In combination in a stop motion for knitting machines, a let-off connection, a member revolving with the machine and movable radially outward therefrom under the influence of centrifugal force, said member being pivoted at its lower end, a yarn engaging portion carried by said member, whereby it is subjected to the restraining influence of the draft of the yarn, a second member pivotally mounted to swing outwardly at its lower end under the influence of centrifugal force, said member having an upper edge extending outwardly from the vertical plane of its pivot and underlying a portion of the first member to rise in front thereof as the second member swings outwardly and thereby oppose the outward movement of said first member under centrifugal force, substantially as described.
20. In combination in a stop motion for knitting machines, a let-off connection, a member revolving with the machine, and subjected to centrifugal force, said member being pivotally mounted at its lower end and movable radially, a second member pivoted near its upper portion and swinging radially in a plane parallel with and alongside of the radial plane of movement of the first member and having its upper edge adapted to restrain the outward movement of the first member and a yarn engaging portion carried by the first member, whereby the draft of the yarn will add its restraint to the restraining influence of the second member against the outward movement of the first member, substantially as described.
21. In combination in a stop motion for knitting machines, a let-off connection, a member pivotally mounted at its lower end and movable radially outward under centrifugal force, said member having a laterally extending portion or pin at or near its upper end, a second member pivotally mounted at its upper end leaving its lower end free to move radially outward under centrifugal force, the upper end of said second member underlying the laterally extending portion or pin on the first member and a yarn engaging portion carried by the first member and adding the restraint of the draft of the yarn to the restraint exerted by the second centrifugal member on the first centrifugal member, substantially as described.
22. In combination in a stop motion for knitting machines, a let-off connection, a bracket adapted to be attached thereto, a member pivotally mounted at its lower end in said bracket, said bracket having a ful-

crum fixed thereto or formed therewith, a 5
feeler lever with which the yarn engages
pivotally mounted at the upper end of said
centrifugal member and engaging the fixed
fulcrum and a second centrifugal member
pivotally mounted at its upper end to a portion
10 of the bracket and coacting with the
portion of the first member to oppose the
movement thereof under centrifugal force,
substantially as described.

23. In combination in a stop motion for
knitting machines, a letoff connection, a
member under stress tending to move radially,
15 a feeler lever pivoted to said member,
a fixed fulcrum engaging said feeler lever,
said feeler lever having a yarn engaging
portion, whereby the draft of the yarn will
exert a restraining influence on the centrifugal
20 member, a yarn carrier, a yarn guide
rotating with the machine and located at a
point above the feeler lever and an adjustable
guide for the yarn mounted on the
machine and adapted to be set at different
25 levels in respect to the feeler lever to change
the angular course of the yarn between the
upper guide, the feeler lever and the adjustable
guide, substantially as described.

24. In combination in a stop motion for
knitting machines, a letoff connection, a
30 member under stress and tending to move
radially outward, a feeler lever pivotally
mounted on the said member and turnable
in a substantially horizontal plane, a fixed
fulcrum for said feeler lever and vertically
35 adjustable yarn guide, means to change the
angular course of the yarn directed to and
from the feeler lever, substantially as de-
scribed.

25. In combination in a stop motion for

knitting machines, a member rotating with 40
the machine and subjected to centrifugal
force tending to move it, a feeler finger
carried by said member and opposing the
movement of the member under centrifugal
force, automatically operating means 45
for compensating for changes in the degree
of centrifugal force to which the said mem-
ber is subjected due to changes in speed, so
that at different speeds said member will be
held by the feeler while the prescribed draft 50
on the yarn is maintained, and a let-off con-
nection, controlled by said member when
the yarn fails, substantially as described.

26. A stop motion unit for knitting ma-
chines comprising a bracket, a member piv- 55
otally mounted thereon, a feeler lever piv-
otally mounted on said member and a fixed
fulcrum carried by the bracket, on which
said feeler lever turns and slides, all of said
parts being attachable to or detachable from 60
the machine as one body, substantially as
described.

27. A stop motion unit for knitting ma-
chines comprising a bracket, a member piv-
otally mounted thereon, a feeler lever piv- 65
otally mounted on said member and a fixed
fulcrum carried by the bracket on which
said feeler lever turns and slides, and a com-
pensating member or weight to be under the
influence of centrifugal force and arranged 70
to oppose the movement of the said pivoted
member under centrifugal force, all of said
parts being attachable to or detachable from
the machine as one body, substantially as
described.

In testimony whereof, I affix my signature.

WILLIAM O. TAYLOR.
